J. A. WILLIAMS AND W. W. WILLIAMS, OF MATTOON, ILLINOIS.

Letters Patent No. 74,468, dated February 11, 1868.

IMPROVEMENT IN SELF-ACTING WAGON-BRAKES.

The Schedule referred to in these Letters Patent and making part of the same.

TO ALL WHOM IT MAY CONCERN:

Be it known that we, J. A. WILLIAMS and W. W. WILLIAMS, of Mattoon, in the county of Coles, and State of Illinois, have invented a new and useful Improvement in Self-Acting Wagon-Brake; and we do hereby declare that the following is a full, clear, and exact description thereof, which will enable those skilled in the art to make and use the same, reference being had to the accompanying drawings, forming part of this specification, in which—

Figure 1 represents a side view of the running-gear of a wagon, with our improved self-acting brake or wheel-lock attached.

Figure 2 is a top view of the same.

Figure 3 is a partial view of the same.

Similar letters of reference indicate corresponding parts.

This invention relates to a new and useful improvement in a wagon-brake or wheel-lock, and consists in a self-acting arrangement of the brake, in connection with the single-trees of a wagon or other vehicle, whereby, when the wagon is descending a hill, it bears upon a wheel and prevents the wagon from running upon the horses, the force of the brake on the wheel being proportioned to the inclination of the road and tendency of the wagon to go forward, so that its movement is regulated automatically, partly by the position assumed by the brake on the wheel, according to the draught, and partly by the action of a spring on the brake, as hereinafter more particularly described.

A A are wheels of a wagon, connected as usual by the reach B with hounds C and tongue D. The shoe α is attached to the end of an iron brake-bar, b , which is bent at right angles, and is attached to the bolster c , to turn loosely in a staple, d , near the middle of the bolster, and at the outer end of the bolster is confined by a link, e , that hooks on to a spring, g , placed on the back part of the bolster. The brake-bar, b , after passing through the staple d , turns downward at right angles, forming an arm, b' , to the end of which is attached a chain, h , made so as to be coupled longer or shorter at pleasure, and fastened at the other end to a rod, k , running under and lengthwise of the wagon, forward of the front axle, where it branches into two forks, $m m$, loosely connected with it, to which forks are fastened chains, $n n$, that are attached to the upper side of the single-trees $p p$ respectively, coming around from underneath.

It will be seen that when the team moves forward, the single-trees draw upon the chains $n n$, and the rod k , and thus operate on the brake-bar b , so that the shoe α rises to the top of the wheel, entirely free from it, and there remains without acting while the draught is continued, but when going down a hill, the wagon tends to crowd the team and the traces slacken, the single-trees drop, and the brake-bar at the same time with them, so that the shoe or rubber falls forward upon the wheel and catches against its periphery, bearing upon it just in proportion to the need of checking the forward movement of the wagon. The spring g bears upon the brake-bar b , by drawing on the link e , and thus presses the shoe α upon the wheel; but the moment the rubbing or pressure of the shoe is greater than is necessary, the team begins to draw upon the single-trees, and thus raises the brake to relieve the pressure of the shoe as required, according to the inclination of the road, and the fluctuation of the draught.

Having thus described our invention, we claim as new, and desire to secure by Letters Patent—

The combination of the brake-bar b , the spring g , the connecting-rod, and chains, and the single-trees p , constructed, arranged, and operating as a self-acting wagon-brake, substantially as herein described.

J. A. WILLIAMS,
W. W. WILLIAMS.
